SAW FILING MACHINE

Frederick J. Knowles, Philadelphia, Pa., assignor
to Nicholson File Company, Providence, R. I., a
corporation of Rhode Island

Application July 24, 1939, Serial No. 286,268

5 Claims. (Cl. 76—35)

This invention relates to saw filing machines and its object is to provide certain detailed improvements in machines of that kind which will produce a strong and rigid structure to thereby obviate any vibration or chattering as the file engages the saw and which will make the operation of such machines smoother and more accurate.

The invention is illustrated in the accompanying drawings forming a part hereof and in which Figure 1 is a side elevation of the machine;

Figure 2 is a front elevation thereof;

Figure 3 is a vertical section on the line 3—3 of Figure 1;

Figure 4 is a vertical section on the line 4—4 of Figure 1;

Figure 5 is a detailed view of the cam and associated parts for producing vertical movement of the bed plate, as later described, this view being taken on line 5—5 of Figure 4; and

Figures 6 and 7 are detailed views of the saw-feeding pawls and associated parts, Figure 7 being a section on the line 7—7 of Figure 6.

Referring to the drawings in detail, the machine comprises a stationary frame or support 10 formed with a bearing 11 in which a main drive shaft 12 is supported, and which may be rotated in any manner desired, as by means of a motor M which drives a belt wheel 13 to rotate the gear wheel 14 secured to said shaft. Rigidly mounted in the frame 10 are two guide bars which are slightly inclined from the vertical, as later explained. Slidably mounted on each bar 15 is a bearing block 16, and coiled springs 17 surrounding the bars 15 tend to force said blocks downwardly. Secured to the bearing blocks 16 is a bed plate 18, provided with an opening 19 through which the shaft 12 extends. A cam 20 is arranged in the opening 19 and secured to the shaft 12, a follower plate 21 on the bed plate 18 being arranged to bear on said cam. Rotation of the shaft 12 will thus produce vertical or substantially vertical reciprocation of the bed plate 18.

The motor M is conveniently mounted on a platform P supported on the upper ends of the bars 15 and on standards 22 secured in the frame of the machine.

The bed plate 18 at its upper edge carries two horizontally arranged bearing blocks 23 rigidly secured thereto in any suitable manner. Slidably mounted in the bearing blocks 23 is a supporting rod 24. Mounted on and supported by this rod is a file carrier plate 25, which is provided on its upper edge with ears 25A vertically

slotted at 26. Clamping bolts 25B extend through these slots and are threaded into the supporting rod 24. The ears 25A extend transversely above the rod 24, and set screws 25C are threaded downwardly through such extensions to engage the top surface of the supporting rod 24. By means of the slots 26 vertical adjustment of the carrier plate 25 may be made, and the bolts 25B serve to hold this plate in any desired position of adjustment. The set screws 25C serve to accurately fix the position to which the plate is adjusted. By the vertical adjustment of the carrier plate 25 the position of the file F relative to the work may be readily and accurately fixed, and the machine may thus be readily adapted for files of different sizes.

Adjacent the end of the shaft 12, the carrier plate 25 is provided with a vertical bearing slot 27. A crank plate 28 is secured to the end of the shaft 12 and this plate carries a roller 29 which is adapted to operate in the slot 27. It will thus be seen that rotation of the shaft 12 will cause horizontal reciprocation of the carrier 25 and the file F mounted therein and also the supporting rod 24 to which the plate is secured. A guide bar 30 extends downwardly from the carrier plate 25 and engages in a slotted guide member 31 secured to lugs 18A on the lower edge of the base plate 18. By this means the plate 25 is accurately guided during the movements thereof.

To support the file F on the carrier plate 25, the latter is provided on one side along its lower horizontal edge with a triangular rib 33, as shown particularly in Figure 3. Mounted on this rib are clamping plates 34, each having a triangular clamping face adapted to fit the rib 33. Cooperating clamping plates 35 are arranged to engage the other side of the carrier plate 25, and the plates 33 and 34 are drawn together by bolts 36. Each of the plates 35 is preferably provided with a pin 35A for engaging a recess in the corresponding plate 34. At their lower ends the plates 34 are slotted and recessed to receive file holders such as shown in my copending application Serial No. 231,991, and in which they may be clamped by bolts 38. By loosening the bolts 36, it is apparent that one or both of the plates 34 with its cooperating plate 35 may be adjusted along the rib 33. Such adjustment of both plates 34 permits the use of files of different lengths and it also enables the travel of the file to be centered relative to the work which results in longer life and more uniform wear of the files. It will be noted further that the

position of the file F is such that the upward thrust on the carrier plate 25 will come between the bearing blocks 23 and will have little or no tendency toward tilting the outer end of said plate upwardly.

To support a saw S during the filing operation, a vise V, such as shown in my copending application Serial No. 243,635, is preferably employed. To feed the saw through the vise, a bell-crank lever 40 is pivotally mounted at 41 on a fixed stud on the stationary frame 10 of the machine. The upper arm of the lever 40 carries an adjustable tappet screw 42 which is positioned to be engaged by a lug or projection 18B on the vertically moving bed plate 18. The lower end of the lever 40 has connected thereto a coiled spring 43 for drawing the same rearwardly, and an adjustable stop screw 44 limits such rearward movement. Two pawls 45 and 46 are pivotally mounted on the lower arm of the lever 40. One of these pawls is arranged to engage the teeth of the saw on one side of the file F and the other on the other side of the file. The pawl 45 is pivoted in the bifurcated lower end of the lever 40 and the pawl 46 is bifurcated to engage over the end of the pawl 45 and the bifurcated end of the lever 40. A pivot pin 47 connects the pawls to the lever 40, and by this arrangement both pawls are mounted on the same pivotal center. The tappet screw 42 and stop screw 44 may be adjusted to secure proper feed of the saw and to accommodate saws with different sized teeth, and the use of two pawls insures accurate and continuous feed of the saw even if one of the pawls fails for any reason to operate properly.

The operation of the machine will be clear without extended description. A saw S is inserted in the vise V and the feed pawls adjusted to give proper feed for the saw in question. Rotation of the shaft 12 causes vertical reciprocation of the bed plate 18 by the cam 20, and horizontal reciprocation of the carrier plate 25 and the file F is produced by the crank 28. Vertical movement of the bed plate 18 also operates the feed pawls 45 and 46 to move the saw step by step beneath the file. The various parts, of course, operate in proper sequence. The file F is brought into engagement with the saw S held in the vise and moves across the same; it is then lifted and returned for another stroke during which time the feed pawls operate to advance the saw another tooth.

Variations in structure may be resorted to within the scope of the invention.

Having thus described the invention, what is claimed as new and desired to be secured by Letters Patent is:

1. In a saw filing machine, in combination, a vertically reciprocating bed plate, a plurality of horizontally spaced bearings carried by said bed plate, a supporting rod slidably mounted in said bearings, a file carrier plate secured to and supported at its upper edge on said rod, means for imparting vertical reciprocating motion to said bed plate and horizontal reciprocating motion to said carrier plate and supporting rod, means for mounting a file on said carrier plate, and means for adjusting said carrier plate up or down relative

to said supporting rod to thereby adjust the position of the carrier plate and the file.

2. In a saw filing machine, in combination, a stationary frame having vertically arranged 5 slightly inclined guide bars mounted therein, a vertically reciprocating bed plate mounted on said bars, and having horizontally spaced bearings thereon, a supporting rod slidably mounted in said bearings, a file carrier plate secured to 10 and carried at its upper edge by said rod cooperating means on said rod and carrier plate for adjusting said carrier plate up or down relative to said supporting rod, file supporting members adjustably mounted on the lower edge of said 15 carrier plate, and means for reciprocating said bed plate and carrier plate and said supporting rod.

3. In a saw filing machine, in combination, a vertically reciprocating bed plate, a horizontally reciprocating carrier plate supported on said bed plate, means for imparting reciprocating motion 20 to said bed plate and carrier plate, means for adjusting said carrier plate vertically relative to said bed plate, said carrier plate having a triangular rib extending horizontally along the lower edge thereof, two file supporting members adjustably mounted on said rib, and each comprising an angular clamping plate and a cooperating plate arranged on opposite sides of said carrier plate and bolted together, the angular clamping plate of each pair being shaped to fit over and being adjustable along said triangular rib on the carrier plate, and file holders carried by said angular clamping plates.

35 4. In a saw filing machine, in combination, a stationary frame, a shaft rotatably supported thereon, two vertically arranged guide bars rigidly mounted in said frame, a vertically reciprocating base plate mounted on said guide bars, a cam on 40 said shaft for reciprocating said base plate, said base plate having horizontally spaced bearings secured to the upper portion thereof, a supporting rod slidably mounted in said bearings, a file carrier plate secured to and supported at its upper edge by said rod, a crank arm carried by said 45 shaft and engaging said carrier plate for reciprocating the same cooperating means on said rod and carrier plate whereby said carrier plate may be adjusted up or down relative to said bearing rod, said means comprising ears on said carrier plate extending above said rod and set screws arranged in said ears and engaging said rod and file supporting members carried by said carrier plate and adjustable horizontally thereon.

55 5. In a saw filing machine, a file carrier plate, a bearing rod to which the upper edge of said plate is secured, means for adjusting said plate up or down relative to said rod, said carrier plate having a horizontal triangular rib extending along the lower edge thereof, two triangular 60 clamping plates adjustably mounted on said rib and spaced apart to receive a file between the same, means for clamping said plates on said rib, file carrying members supported by said clamping plates and means for horizontally reciprocating said carrier plate and bearing rod.

FREDERICK J. KNOWLES.
